UNITED STATES PATENT OFFICE.

HARRY B. GOLDSTEIN, OF ST. PAUL, MINNESOTA.

FORM FOR HAT-CROWNS.

1,381,915.

Specification of Letters Patent. Patented June 21, 1921.

Application filed May 18, 1920. Serial No. 382,303.

To all whom it may concern:

Be it known that I, HARRY B. GOLDSTEIN, a citizen of the United States, residing at St. Paul, in the county of Ramsey and State of Minnesota, have invented a new and useful Improvement in Forms for Hat-Crowns, of which the following is a specification.

My invention relates to hat forming 10 crowns, which are used for the purpose of blocking or renovating new or old hats made of hair braid, velvet, crinoline, lace or any other suitable material out of which hats and their linings are made. The primary 15 object is the production of a forming device of the class stated, which can be used for blocking and repairing the crowns and brims of hats with greater efficiency. A further object is to provide a simple and inex- 20 pensive metallic non-corrodible form for the purpose stated, which can easily be taken apart for cleaning or packing and which can be easily and quickly assembled and used. A still further object is the produc- 25 tion of a device of the character stated, which is particularly adapted for use by milliners or in factories, the cost of the device being comparatively low and the device being portable and easily set up for use 30 without the use of any tools or mechanical power.

In the accompanying drawing forming part of this specification, Figure 1 is a longitudinal vertical section of my invention, 35 showing the parts in assembled position; Fig. 2 is a vertical section of a detail showing a portion of the crown and a portion of the fabric of the crown and brim of the hat pinned thereto; Fig. 3 is a bottom plan of 40 the brim plate, and Fig. 4 is a top plan of the stand.

In the drawing, A indicates my improved 45 hat blocking crown, which is preferably made out of thin rust proof solid metal, molded or formed into the shape it is desired to make the crown of a hat. This forming crown is made with a thin rigid wall B of substantially even thickness, out 50 of aluminum or other suitable rust proof smooth material, the outer surface of said wall conforming in shape, style and size with the inner surface of the hat crown, which it is desired to mold or shape. The crown is placed substantially in the center 55 of a brim supporting plate C, which conforms in size and shape with the brim of

the hat to be formed, the shape shown being adapted to support a flat brim. This brim plate has a plain upper surface and lower inwardly slanting circular guide 60 shoulder D, which corresponds with a circular recess E in the upper end of a stand F. This stand has a plurality of supporting legs G and its upper end has an opening H across which is a supporting bar I. 65 The brim plate also has a corresponding opening J and supporting bar K. These two bars are revolvably tied together by a pivot bolt L, a spacing element M on the bolt being placed between the bars, so that 70 the brim plate will revolve freely with the shoulder D substantially out of contact with the inner surface of the recess E, said shoulder and surface of the recess serving to steady the brim plate on the stand. A 75 heater N is adapted to be placed within the stand and is provided with one or more crown burners O, the flame from which circulates upwardly through openings H and J into the crown, thereby heating the crown. 80 The heater N is also provided with branch burners P projecting outwardly through the side of the stand to points in close proximity to the lower surface of the outer portion of the brim plate, thereby serving to 85 heat the plate independently of the crown heating burner or burners. The lower edge of the crown element B has secured to it a soft buffer strip Q by stitching R or other suitable means passing through perforations 90 S. This strip permits the lower edges of crinoline crowns U (see Fig. 2) when stretched and preferably moist to be secured by pins T to the crown element B. In this condition the heated crown element 95 will dry and thus block the hat crown.

In use the crown element B is placed in the center of the brim plate over the openings J and H and the heater operated within the stand. The hat or crinoline crown to 100 be blocked is adjusted over the crown element. When the crown alone is blocked it can be stretched and fastened to the buffer strip, but when the entire hat is to be blocked, it is placed over the crown element and its brim 105 allowed to lie flat on the brim plate. The burners are operated to heat the crown element or the crown element and brim plate as desired to complete the blocking operation. During the adjustment of the crino- 110 line crown on the entire hat over the parts as mentioned, the brim plate can be turned

by hand on the stand to facilitate making the adjustment. Any kind, size or shape of crown element can be used on the brim plate, thus necessitating carrying in stock 5 only such crown elements as are used in connection with a particular kind of rim. The brim plate can also be removed from the stand by detaching the pivot bolt and a different kind, size or shape brim plate 10 substituted for use with the same set of crown elements. The crown element can be used with an enveloping form over the crown of the hat to hold and press the hat on the crown element and brim plate when desired. The invention provides a simple, inexpensive and effective device for blocking hats in factories and milliner shops without the use of expensive machinery as heretofore. The parts of my invention can be 15 made out of rust proof metal such as aluminum to advantage.

Having described my invention what I claim as new and desire to protect by Letters Patent is:

25 1. A hat blocking device, comprising, in combination, four coöperating elements, one a portable stand, another a brim supporting plate held by said stand and having an air circulating passage near its central portion 30 another a crown element placed over said passage with its lower edge resting on said brim plate, and the other a heater having a burner placed below said passage in position

to circulate heated air and gases up through said passage to heat said crown element. 35

2. A hat blocking device, comprising, in combination, four coöperating elements, one a portable stand, another a brim supporting plate held by said stand and having an air circulating passage near its central portion 40 another a crown element placed over said passage with its lower edge resting on said brim plate, and the other a heater having a burner placed below said passage in position to circulate heated air and gases up 45 through said passage to heat said crown element, said heater being also provided with a burner placed immediately below the outer portion of said brim plate to heat the latter.

3. A hat blocking device, comprising, in combination, four coöperating elements, one a portable stand, another a brim supporting plate journaled on said stand adapted to revolve in a horizontal plane and having an air circulating passage near its central portion 50 another a crown element placed over said passage with its lower edge resting on said brim plate, and the other a heater having a burner placed below said passage in position to circulate heated air and gases 55 up through said passage to heat said crown element. 60

In testimony whereof, I have signed my name to this specification.

HARRY B. GOLDSTEIN.
